ATTORNEY

UNITED STATES PATENT OFFICE

NANCY E. MAPHET, OF WICHITA, KANSAS

INVALID'S SUPPORT

Application filed May 31, 1930. Serial No. 458,123.

This invention relates to new and useful improvements in invalid's supports and has for the primary object, the provision of a device of the above stated character which will be comfortable to a person, permitting the person to be efficiently supported in a sitting position with means engaging under the arms to aid the person in remaining in such a position and to permit the nurse or attendant to move the invalid from one place to another.

Another object of this invention is the provision of means whereby the device may be easily employed as a commode when necessary without entirely removing the invalid from the support.

A further object of this invention is the provision of an invalid's support of the above stated character which will be simple, durable and efficient, and which may be manufactured and sold at a comparatively low cost.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawing, in which:

Figure 1 is a perspective view illustrating an invalid's support constructed in accordance with my invention.

Figure 2 is a top plan view illustrating the same.

Figure 3 is a side elevation illustrating the device positioned ready to receive an invalid.

Referring in detail to the drawing, the numeral 1 indicates a supporting frame including converging corner posts or members 2 connected at spaced intervals by upper, intermediate and lower braces 3, 4 and 5 respectively and the posts or members 2 have secured to their lower ends suitable casters 6 whereby the device may be easily moved from one place to another, either when occupied or unoccupied. The braces 3, 4 and 5 are omitted between the rear and front posts 2 at one side of the device to form an entrance-way which is normally closed by a gate or

door 7. The gate or door 7 is hinged to the rear post as shown at 8 and detachably secured to the front post by hooks or similar fasteners 9 providing a construction which will permit an invalid person to be easily placed in or removed from the frame 1.

A seat 10 is carried by the frame 1 and the front and rear braces at the upper ends of the frame have detachably secured thereto arm straps 11 adapted to be positioned under the arms of an invalid located on the seat 10 to aid in supporting the invalid within the frame in a seated position. The invalid may rest upon the straps 11 consequently relieving some of the weight on that portion of the invalid's body resting upon the seat 10.

The seat 10 includes upper and lower members 12 and 13 hinged together as at 14 and the member 13 is secured to suitable braces 15 which are in turn secured to some of the braces 4 and 5 of the frame 1. The member 13 is provided with the usual commode opening and is normally closed by the member 12 providing a comfortable seat for the invalid when not employed as a commode. A shelf 16 is hinged to the braces 15 at one end and underlies the seat 10 and is provided with a detachable support 17 at the free end to permit the shelf to be swung upwardly under the seat when not supporting a commode. It is to be understood that the commode rests upon the shelf 16 directly under the opening in the member 13 and may be easily removed therefrom by the attendant.

From the foregoing description taken in connection with the accompanying drawing, it will be noted that an invalid may be easily placed in and removed from the device through the entrance-way formed in one side of the frame 1 and normally closed by the door or gate 7 and when the invalid is positioned on the seat 10 and supported by the straps 11 under the shoulders, the invalid may then be moved by an attendant or nurse from one place to another and also when desiring to use the commode it is only necessary to raise the invalid slightly in order to swing the member 12 upwardly and permit the invalid to rest on the member 13. If desired the casters 6 may be covered with

rubber or any other suitable material for the purpose of deadening the sound and to increase the comfort and ease in which the invalid may be moved from one place to another within the frame.

While I have shown and described the preferred embodiment of my invention, it will be understood that minor changes in construction, combination and arrangement of parts may be made without departing from the spirit and scope of the invention as claimed.

Having thus described my invention, what I claim is:

- 15 An invalid's support comprising converging corner posts, upper, lower and intermediate braces connecting said posts and omitted between a pair of said posts to provide an entranceway, a seat carried by a pair of posts
- 20 with the entranceway arranged at one side of the seat to permit placing of a person on the seat by way of the entranceway while occupying a substantial sitting position, a solid door for closing the entranceway and providing a shield for the person on the seat and hinged to one of the posts and detachably secured to another post, and spaced straps secured to opposite upper braces and adapted to extend under the arm pits of the person
- 25 on the seat to support said person in a sitting position, leaving the arms of the person free for use and disposed within the device.

In testimony whereof I affix my signature.

NANCY E. MAPHET.
